UNITED STATES PATENT OFFICE.

LEWIS S. CHICHESTER, OF BROOKLYN, NEW YORK.

IMPROVEMENT IN HEMP-BRAKES.

Specification forming part of Letters Patent No. **8,700**, dated February 3, 1852.

To all whom it may concern:

Be it known that I, LEWIS S. CHICHESTER, of Brooklyn, in the county of Kings and State of New York, have invented a certain new and useful Machine for Breaking, Cleaning, and Softening Flax and Hemp or other like Fibrous Materials; and I do hereby declare that the following is a full, clear, and exact description of the same, reference being had to the accompanying drawings, making part of this specification, in which—

Figure 1 is a side elevation; Fig. 2, a plan; Figs. 3 and 4, longitudinal vertical sections taken at the lines A a and B b, Fig. 2; and Fig. 5, a longitudinal section of one of the cylinders.

The same letters indicate like parts in all the figures.

The object of my invention is to thoroughly break flax or hemp or other fibrous material and separate the woody parts from the fibers and the fibers from each other by one single but continuous operation, and to effect this by a mechanical operation in which the material shall be grasped and held at two different points and on opposite sides, and held by spring-pressure so loosely as to permit slipping without undue or injurious strain on the fibers, and yet so firmly as to permit the two surfaces that grasp it at one point to slide back and forth nearly at right angles to the line of motion of the material, and by the side of other surfaces that grasp it at another point, and at the same time have the grasping-surfaces to move along with the material that other surfaces may in succession grasp it at different points along the length of the mass until the whole mass is passed through and other masses in succession, the object being to produce on the material to be broken and cleaned a mechanical action resembling that which would be produced if a piece of the material were grasped at one point by the thumb and finger of one hand and at a short distance therefrom by the thumb and finger of the other hand, and then moving the two hands in opposite directions until the material be bent in two places nearly at right angles, and then, without drawing the hands apart, moving the two back and forth in opposite directions, so as to crush into minute particles the woody part and other impurities that adhere to and connect the fibers; and to effect this purpose the

nature of my invention consists in combining together two cylinders or rollers geared together, so as to rotate with equal velocities, and in opposite directions, which cylinders have their peripheries composed of fixed rods extending from end to end and parallel with each other, and having spaces between them, in which are fitted radial plates that are made to slide in and out radially with a rapid vibratory motion to a determined distance beyond and within the fixed rods, and the said cylinders being so geared that in their rotation the rods and sliding plates of one shall come opposite to those of the other, to grasp and carry forward the material, or in having one or more cylinders or rollers, as above, and working with another roller or rollers made with fixed projecting plates instead of the sliding plates, and so geared that in the rotation of the several rollers or cylinders the fixed projecting plates of the one shall come opposite to and grasp the material to be broken or cleaned on the edge of the sliding plates of the other and force it in between the parallel rods. And the nature of my invention also consists in combining springs with the said sliding or vibrating plates for the purpose of forcing the plates outward from the center of each cylinder, so that in grasping the material they shall be self-adapting and avoid undue strain on the fibers when under the action of the vibratory motion. By this means, as the two cylinders rotate, the material is carried through between them and grasped at different points between the fixed rods by the movable plates of the two cylinders, and when thus held between the movable plates of the two cylinders by the action of the cams and springs they are vibrated rapidly in and out, which has the effect to break and pulverize the woody parts of the material and to crimp and rub the fibers, and thus effectually remove from them foreign matter and separate them from each other.

In the accompanying drawings, *a* represents the frame, which may be varied at pleasure; and *b b'* the two breaking and cleaning cylinders or rollers properly mounted on parallel shafts *c c'*, which are geared together by two cog-wheels, *d d'*, so as to turn in opposite directions with equal velocities. One of the cog-wheels, *d'*, engages a cog-wheel, *e*, on the driving-shaft *f*, to communicate the required

motion to the two cylinders from some first mover. As the two cylinders are constructed in like manner, the description of one will be sufficient.

On the shaft *c* there are two heads, *gg*, with radial slots *h* extending from about the middle of the radius to within a short distance of the periphery. The grooves have parallel sides. To the heads are secured round rods *i*, extending from one head to the other in lines parallel with the axis and at such distances apart as to leave spaces between them equal or nearly equal to their diameter; and in the spaces between the rods are inserted radial plates *j*, which play freely between them, the ends of the said plates being fitted to slide in the radial slots in the two heads and projecting for a short distance outside of the heads. The outer edges of these plates are slightly rounded, and the ends that play in the radial slots are cut down from the outer edge, so that their outer edges can be made to project beyond the rods *i* to a distance about equal to the diameter of the rods, more or less. Between the two heads, and attached to the shaft at proper distance apart, are two disks, *k*, *k*, of vulcanized india-rubber, on which the inner edges of the plates rest, and which tend by their elastic force to keep the plates out as far as they are permitted to go, and which, however, permit them to be pushed in. The two cylinders thus constructed are mounted and geared so that in their rotation the rods and plates of one will come opposite to the corresponding rods and plates of the other, and at such a distance apart that a mass of the material properly spread out will pass freely between the plates of the two cylinders. The springs that act on the plates of the upper cylinder should be of greater tensile force than those on the lower cylinder, and sufficiently so to force in the plates of the lower cylinder when the position of the cams will permit it, as hereinafter described.

At each end of the lower cylinder, *b'*, is mounted a cam-wheel, *l*, fitted to turn on its shaft, and with the periphery formed with cam-like projections *m* within the inner edge of the plates *j*. These cams are of such form as to permit the outer edge of the plates *j* of this cylinder to be forced within its periphery by the tension of the springs acting on the plates of the other cylinder, *b*, and then to force them out beyond the periphery, and in turn to force the plates of the cylinder *b* within its periphery. Each cam-wheel carries a pinion, *n*, which engages a cog-wheel, *o*, that receives motion from a cog-wheel, *p*, on the main driving-shaft *f*, so that the cam-wheels will turn in the reverse direction of the cylinder and with a much greater velocity. There is a feeding-table, *q*, in front, on which the material to be broken is placed by the operator, and from which the cylinders are supplied, and a receiving-table, *r*, on the other side, onto which the material is delivered from the cylinders.

From the foregoing it will be seen that when

the cylinders are moved in the direction of the arrows and fibrous material is supplied to them, it will be gripped by and between the corresponding plates of the two cylinders by a force depending on the tension of the springs and carried forward, and as it passes the bite of the two cylinders, and while between the fixed rods *i*, *i* of the two cylinders, by the action of the cam-wheels on the plates of the cylinder *b'* and the springs acting on those of the other cylinder, *b*, a rapid in-and-out motion is imparted to the plates, which has the effect of forcing the material alternately and with a rapid motion against and by the fixed rods, first of one cylinder and then of the other, and thus to break the woody part of the material; and as it is gripped between the plates simply by the force of the springs, and it is thus gripped at several parts of the length, as the plates slide to carry it between two of the fixed rods of one of the cylinders it drags between the several plates to obtain the required length for the bend thus produced, and after it has been thus bent in one direction, and while it is still gripped at two or more points between two or more sets of plates, the plates vibrate in the opposite direction, which has the effect to crimp up and thoroughly pulverize the woody parts, and at the same time to separate the fibers from each other, and from foreign matter, and also to soften the fibers. The larger the cylinders the greater will be the number of plates acting simultaneously on the material, and the greater the number of cam-projections on the wheels and their velocity the greater will be the amount of breaking, crinkling, and rubbing action on the fibers.

Instead of having the two cylinders or rollers made, as above described, one of them may be made with fixed projecting plates instead of the sliding plates, and the two cylinders so geared that in their rotation the fixed plates of the one shall grasp the material to be broken or cleaned on and against the edge of the sliding plates of the other, and thus force in the material between the rods.

Instead of two cylinders, two or more may be employed in succession, or several small cylinders may be arranged around the periphery of one large one, and in such case the large one may be made with sliding plates, and all of the small ones in like manner, or with fixed projecting plates, or some with sliding and others with fixed plates.

I do not wish to limit myself to the special construction of the parts and their arrangement, as these may be greatly varied within the range of the principle or character of my invention. The cylinders, instead of being placed one above the other, may be placed side by side in the same horizontal plane. The springs for forcing out the plates may be made of suitable material other than india-rubber and of any suitable form. The cams may be varied in number, shape, and position so long as they act on the plates to force them

outward, and permit them in return to be forced inward by the plates of the other cylinder to produce the peculiar vibratory action on the material from the one cylinder to the other as the two cylinders rotate to carry the material forward; and, finally, the gearing may be varied at pleasure so long as the two cylinders are rotated with equal velocities to insure the proper relative position of the rods and plates of the two cylinders, and the motion of the cams in opposite direction to the cylinder with which they are connected, or in the same direction with greater velocity; nor do I wish to be understood as limiting myself to the use of cams to operate the sliding plates of one cylinder, as cams may be used to operate the plates of both cylinders, or the plates of one cylinder may be connected with the plates of the other cylinder by means of links with or without the interposition of springs, and thus operate the two sets by one set of cams; nor do I wish to limit myself to the use of both parts of my invention in one and the same machine, as it may operate without the employment of springs in combination with the sliding plates, but it will produce a better effect with the spring.

What I claim as my invention, and desire to secure by Letters Patent, is—

1. Making two or more breaking and cleaning cylinders with fixed rods at or near their peripheries, and radial plates made to slide radially, (or some of them fixed,) operated, substantially as herein described, in the spaces between the rods, substantially as described, the two or more cylinders being geared together so as to turn with equal velocities, and so placed that in their rotation the rods and plates of one cylinder shall come opposite to those of the other cylinder, for the purpose and in the manner substantially as set forth.

2. The combination of springs, substantially as described, with the sliding plates of the cylinder or cylinders, operated, substantially as herein described, for the purpose of rendering the plates self-adapting to the material introduced, and insure its being properly gripped and held, so as to admit of slipping without undue strain on the fibers, as described.

LEWIS S. CHICHESTER.
